SET UP MACHINE FOR EGG CARTONS
Richard J. Fahey, Glenview, Ill., assignor to Michigan
Carton Company, Battle Creek, Mich., a corporation of
Michigan

Filed May 28, 1962, Ser. No. 193,144
25 Claims. (Cl. 93—37)

This invention relates to a method and apparatus for setting-up or erecting paperboard cartons and, in particular, relates to a method and apparatus for setting-up or erecting a collapsed paperboard carton blank into a cellular carton of the type used for receiving and storing eggs.

It has heretofore been proposed to set-up or erect cartons, such as cellular egg cartons, by providing an apparatus comprising several set-up instrumentalities for successively acting upon collapsed paperboard carton blanks which are supplied one at a time from a stack thereof contained in a supply magazine. With specific reference to the set-up of cartons for receiving and storing a plurality of eggs, such a collapsed carton blank is characterized by a connected series of panel members adapted to be erected into top, side and bottom wall forming members of the finally set-up carton, and further includes cross partition forming panel members foldable out of the plane of the top wall forming member into interlocking engagement with the bottom wall forming member to form the finally set-up or erected carton and the cell structure thereof for receipt of the eggs. The set-up apparatus and methods of the prior art have typically included means for feeding collapsed carton blanks from the aforementioned supply magazine one at a time to a set-up zone in which means are provided for successively at least partially expanding the carton blank and disposing the top wall forming member thereof in engagement with a reciprocable set-up head equipped with a plurality of pivoted folding plates or leaves adapted to engage and fold the cross partition forming panel members out of the plane of the top wall forming member for subsequent interlocking engagement with the bottom wall forming member of the carton blank which is then tucked into engagement therewith by a suitable tucking means. While such prior apparatus and methods have been employed with considerable success, they have presented certain problems which seriously detract from the overall efficiency of the carton set-up or erecting operation, and frequently malfunction in properly erecting egg cartons thereby resulting in considerable waste in paperboard carton blanks, and otherwise.

For example, prior apparatus of the type in question particularly adapted for setting-up or erecting egg cartons have typically comprised a relatively great number of set-up instrumentalities such as a feeding mechanism, arresting mechanism for a carton blank being fed by the feeding mechanism, mechanism for partially expanding the carton blank, mechanism for operating the set-up head and additional mechanism for operating the pivotal folding plates or leaves carried thereby, mechanism for accomplishing final set-up or erection of the carton blank by tucking the bottom wall forming member thereof into interlocking engagement with the cross partition forming members and mechanism for ejecting a fully set-up or erected carton from the apparatus, most if not all of such mechanisms or instrumentalities being individually controlled by separate drive means including drive cams, follower rods and linkages and the like. Consequently, it has been necessary to utilize rather elaborate drive and linkage systems in connection with such mechanisms or instrumentalities so as to interrelate their individual operating actions to the successive sequence of operations desired to be made in fully erecting a carton from a col-

2

lapsed paperboard carton blank. As a result, considerable care must be taken in adjusting and servicing each of the individual drive mechanisms for each of the set-up instrumentalities not only to insure proper operation of the particular instrumentality involved in performing its intended function, but also to insure that each such instrumentality operates in proper timed relationship with respect to the other instrumentalities.

Furthermore, the magazine structures of such prior art apparatus have included oppositely facing wall means rigidly secured to the apparatus in predetermined spaced relationship to receive collapsed carton blanks or a stack thereof of a predetermined size. Consequently, on those occasions when it is desired to erect carton blanks of a dimension differing from those of the carton blanks for which the magazine was particularly designed, it has been necessary to adjust the spacing of the wall means of the original magazine or completely replace the latter to accommodate the stack of carton blanks having the different dimensions. As a consequence, considerable "down" time may result during adjustment or replacement of the magazine, thereby detracting from the overall efficiency of the apparatus.

In addition, in one known apparatus of this type, a plurality of pick-up cleats or fingers are mounted on the leading or feeding edge of a feed mechanism so as to engage in corresponding pick-up openings in the lowermost collapsed carton blank of a stack thereof contained in the aforementioned supply magazine so as to feed said lowermost carton blank from the stack into a set-up zone on the apparatus. However, it frequently happens that one or more of the pick-up fingers or cleats carried by the feed mechanism extends not only into the lowermost carton blank in the stack, but also into the blank immediately thereabove, thereby resulting in the feed mechanism attempting, if not successfully so, to feed two carton blanks to the set-up instrumentalities in the set-up zone. Such a situation is intolerable in an apparatus of the type in question, and merely results in waste in the carton blanks since the set-up instrumentalities are incapable of acting upon carton blanks fed more than one at a time.

Furthermore, in addition to pick-up of the lowermost carton blank in the stack thereof in the magazine, it is quite important that the lowermost carton blank be positioned properly for cooperating engagement between the pick-up openings therein and the pick-up cleats or fingers on the feed mechanism of the prior art. However, it happens that a given carton blank may become misaligned relative to the feed mechanism of the prior art as the blank descends in the stack in the magazine, resulting in failure to feed such carton blank and further waste.

In addition, in known apparatus of the type in question, the feed mechanism is additionally equipped with a plurality of ejecting fingers or cleats along the leading or feeding edge thereof and extending therebeyond, and adapted to engage a portion of an erected carton to eject the latter from the set-up zone of the apparatus as the feed mechanism feeds a successive carton blank for erection by the set-up apparatus. More specifically, these ejecting fingers or cleats have been adapted to engage with an edge of a locking strip or panel at one end of the carton blank which, upon erection of the carton, is adapted to engage therewith to close the top of the carton and enclose the eggs therein. It sometimes happens that a certain amount of warpage occurs along the aforementioned edge of the locking strip or panel causing the edge thereof to be bowed upwardly from the path of the feed mechanism equipped with the ejecting fingers or cleats, thereby frequently resulting in the ejecting fingers or cleats being unable to reach the afore-

mentioned edge of the locking strip or panel to perform the ejecting operation.

By way of further example, one of the more serious problems presented by apparatus of the type in question and heretofore known resides in operation of the aforementioned set-up head and the pivotal folding plates or leaves carried thereby for folding the cross partition forming panel members of the carton blank into position for interlocking engagement with the bottom wall forming member of the carton upon final set-up. More specifically, in one type of known apparatus, the set-up head has been mounted for oscillatory movement between the supply magazine containing the stack of collapsed carton blanks and a set-up zone in which the set-up operation occurs, and the folding plates or leaves have been relatively impositively actuated; that is, as a function of the oscillatory movement of the set-up head itself and without any direct or positive relation to the position of the carton blank being set-up or other set-up instrumentalities of the apparatus. Thus, it frequently happens that the folding plates are partially operated and pivoted before they even engage the cross partition forming panel members of a partially erected carton, thereby resulting in the folding plates or leaves attempting to pierce through the cross partition forming members rather than folding them into position for operative engagement with the bottom wall forming member of the carton blank. It was a recognition of these and other problems in this art that led to the conception and development of the present invention.

Therefore, the objects and features of the present invention include the provision of an improved set-up apparatus and method by which successive collapsed paperboard carton blanks may be fed one at a time from a magazine and set-up quite rapidly and efficiently into erected cellular cartons of the type particularly adapted to receive eggs, while avoiding one or more of the problems discussed above as well as others.

It is yet another object and feature of this invention to provide an improved set-up apparatus and method by which successive collapsed paperboard carton blanks may be fed one at a time from a magazine and set-up quite rapidly and efficiently into erected cellular cartons of the type particularly adapted to receive eggs through the timed coaction of various set-up instrumentalities, the operation of which is so interrelated as to be operable in response to one relatively simple drive means or drive train.

It is yet another object and feature of this invention to provide an improved set-up apparatus and method by which successive collapsed paperboard carton blanks may be fed one at a time from a magazine and set-up quite rapidly and efficiently into erected cellular cartons of the type particularly adapted to receive eggs through the timed coaction of various set-up instrumentalities including a pair of set-up heads and a folding head, all of which are mounted for rectilinear reciprocation along the apparatus relative to a set-up zone thereon, a single drive means being provided for connection to the aforementioned folding head and the latter coacting in such a manner during reciprocable movement thereof to provide the drive required for reciprocating the two set-up heads aforementioned in erecting the collapsed paperboard carton blank.

It is yet another object and feature of this invention to provide an improved carton set-up apparatus and method including means in association with the supply magazine for a stack of collapsed carton blanks for aligning carton blanks one above the other in at least the lower portion of the stack, to facilitate feed thereof to a set-up zone on the apparatus.

It is yet another object and feature of this invention to provide a method and apparatus for erecting or setting-up cellular paperboard cartons from a collapsed paperboard carton blank characterized by improved means for

feeding the carton blanks one at a time from a stack contained in a magazine, and which means eliminates the need for pick-up openings in a carton blank to be fed and the necessity of a pick-up cleat or finger entering such opening during the feeding operation, thereby eliminating the problems presented by the prior art and as aforementioned in this regard.

It is yet another object and feature of this invention to provide a method and apparatus for erecting or setting-up cellular paperboard cartons from a collapsed paperboard carton blank characterized by an improved means for ejecting a fully set-up or erected carton from the apparatus without requiring the ejecting cleats or fingers of the prior art on the feed mechanism, and which improved ejecting mechanism is operable irrespective of any warpage which might occur in any part of the fully erected carton, and particularly that part engageable with the improved ejecting mechanism.

It is a further object and feature of this invention to provide an adapter means for a supply magazine of the type comprising oppositely fixedly spaced wall means for receiving stacks of collapsed carton blanks of two different dimensions therebetween, and characterized by the fact that the adapter means includes an adapter member adjustably mounted on one of the wall means of the magazine and provided with two carton blank-engaging surfaces selectively disposable within the magazine to varying extents to provide support for stacks of collapsed carton blanks of two different dimensions.

It is yet another object and feature of this invention to provide a method and apparatus for setting-up a collapsed paperboard carton blank into an erected cellular carton of the type adapted to receive a plurality of eggs nested therein comprising means for feeding successive collapsed carton blanks one at a time from a supply magazine to a set-up zone on the apparatus, means including a pair of set-up heads for confining said carton blank in said set-up zone to move the side wall forming members thereof away from each other to at least partially expand said blank with the top and bottom wall forming members thereof connected between said side wall forming members opposite to each other and engaged by respective ones of said set-up heads, means for holding said set-up heads and hence the top and bottom wall forming members of the carton blank substantially stationary while reciprocating a folding head relative thereto to fold the cross partition forming members of the carton blank between said side wall forming members thereof and toward the bottom wall forming member thereof, and means for reciprocating said set-up and folding heads in unison and relative to a fixed tucking plate or blade engageable with the bottom wall forming member of the carton blank to tuck the latter toward and into interlocking engagement with the folded cross partition forming members to fully erect or set up the carton.

It is yet another object and feature of this invention to provide a method and apparatus for setting-up a collapsed paperboard carton blank into an erected cellular carton as aforementioned, further characterized by a single motor driven drive means operatively connected to the aforementioned folding head and providing all drive required for reciprocating said folding head and the aforementioned set-up heads during the erection and set-up of a carton blank into a fully erected cellular carton.

Still further objects, features and advantages of the invention will appear as the description proceeds.

To the accomplishment of the foregoing and related ends, the invention, then, consists of the steps and means hereinafter fully described and particularly pointed out in the claims, the annexed drawings and the following description setting forth in detail certain means and modes of carrying out the invention, such means and modes illustrating, however, but one of the various ways in which the principle of the invention may be used.

In the annexed drawings:

FIGURE 1 is a side elevation, partly in section and partly broken away to illustrate certain details, of a preferred embodiment of the invention in an egg carton set-up apparatus, and illustrates the positions of various set-up instrumentalities thereof just prior to feeding a collapsed paperboard carton blank into the set-up zone of the apparatus where final carton set-up or erection takes place;

FIGURE 2 is a top plan view of FIGURE 1;

FIGURE 3 is a sectional view, partly broken away to illustrate certain details, taken on line 3—3 of FIGURE 1;

FIGURES 4 through 8 are fragmentary side elevations corresponding generally to FIGURE 1, but illustrating the various relative positions of the various set-up instrumentalities during steps in the set-up or erection process succeeding the position illustrated in FIGURE 1;

FIGURE 9 is an enlarged fragmentary view of FIGURE 2 illustrating certain details of the folding head and a set-up and feeding head of the apparatus;

FIGURE 10 is an end view of FIGURE 9 looking in the direction of the top of the drawing;

FIGURE 11 is a further fragmentary view, partly in section, of FIGURE 2 illustrating certain details of the supply magazine of the apparatus;

FIGURE 12 is a fragmentary sectional view taken on line 12—12 of FIGURE 11; and

FIGURE 13 is a perspective view of one type of collapsed paperboard carton blank adapted to be set-up into an erected carton by the apparatus and method of this invention.

In FIGURE 13, the numeral 20 generally designates a type of collapsed partially folded paperboard carton blank which is adapted to be manipulated and set-up into an erected "summit type" carton for subsequent use; that is, a carton blank of the type which, when fully erected, provides a "summit" or medial row of partitions between the front and rear side walls thereof to provide additional support for the cover forming portion of the fully erected carton when locked into position in the carton to enclose eggs therein. As is well known in the art, a carton blank of this type is formed from a unitary paperboard blank which is cut, creased, folded and glued so as to result in the collapsed carton blank illustrated in FIGURE 13, which also illustrates the condition of the carton blank as it is supplied to the user thereof. However, as will also be appreciated by those acquainted with this art, carton blanks other than those specifically designed for the erection of "summit type" cartons may likewise be employed in accordance with the invention, as will become more readily apparent hereinafter.

More specifically, and referring particularly to FIGURES 8 and 13, the carton blank 20 comprises a relatively narrow locking panel or strip 22 extending across one end of the blank from which the carton blank is formed, and includes a plurality of spaced locking hooks 24 along its free edge. The locking panel or strip is bendable along the fold line 26 with respect to a cover forming panel member 28 adapted to close the top of an erected carton upon engaging the locking hooks in one edge thereof. The cover forming panel member is bendable along a fold line 30 with respect to one side wall forming panel member 32 which is bendable along the fold line 34 with respect to one bottom wall forming panel member 36 which is, in turn, bendable with respect to another substantially duplicate bottom wall forming panel member 38 along the medial fold line 40. The other bottom wall forming panel member 38 is, in turn, bendable along a fold line 42 with respect to the other side wall forming panel member 44 which is substantially a duplicate of the side wall forming panel member 32. A pair of top wall forming panel members are indicated generally at 46 and 48 in FIGURE 13, and are joined together by the medial fold line 50. Referring particularly

to FIGURE 13, each top wall forming panel member includes a plurality of interconnected cross partition forming panel members 52 and 54 which are separable along the score lines 56 by a folding means to be hereinafter described, and are foldable out of the respective planes of the top wall forming panel members 46 and 48 inwardly of a partially erected carton for subsequent engagement with the bottom wall forming panel members 36 and 38.

10 To this end, one end of each of the cross partition forming panel members 52 and 54 is swingably connected to one edge of the side wall forming panel member 44 by means of small tabs jointed on fold lines indicated at 58, while the other ends of the cross partition forming panel members are similarly swingably connected to an elongate terminal glue strip 60 attached by glue or other adhesive to the inner surface of the side wall forming panel member 32.

A row of spaced elongate openings including hook members 62 extend along the respective bottom wall forming panel members 36 and 38 in opposition to each other, and are adapted to be tucked inwardly of a carton during erection or set-up thereof for engagement with a plurality of locking apertures including bridging members 64 spaced along the medial fold line 50 between the top wall forming panel members 46 and 48. Additionally, upon folding or swinging the cross partition forming panel members 52 and 54 out of the plane of the top wall forming panel members inwardly of the carton during the erection of the latter, the terminal ends of the cross partition forming members 52 are adapted to be received within a plurality of spaced locking slits 66 formed in the bottom wall forming panel members 36 and 38. Furthermore, and as will be readily apparent, a plurality of spaced tongues 68 project from the medial fold line 40 separating the bottom wall forming panel members 36 and 38 and, after the bottom wall forming panel members are tucked inwardly of the carton as aforementioned, will extend between respective pairs of the cross partition forming panel members 52 and 54 to form therewith a crown or "summit" support for the cover forming panel member 28 foldable thereover to enclose eggs within the carton.

As is clearly indicated in FIGURE 13, in its collapsed or knocked down condition, the carton blank 20 is partially folded upon itself along the medial fold line 40 at one end thereof and again at the medial fold line 50 to permit securing the terminal glue strip 60 to the side wall forming member 32. As a result, the respective side, bottom and top wall forming panel members including the cross partition forming panel members aforementioned overlie each other and form a double ply thickness of the carton blank material extending from one end thereof through somewhat more than one-half of its length, the cover forming panel member 28 and locking panel or strip 22 being, therefore, of single ply. A plurality of collapsed cartons as illustrated in FIGURE 13 and suggested by FIGURE 1 are adapted to be stacked one upon the other in a supply magazine with the cover forming panel member 28 and the panel members connected thereto lying on top, and the edge of the carton blank at the medial fold line 40 forming the leading edge of a carton blank fed from the magazine.

Referring now particularly to FIGURES 1 through 3, the drawings illustrate an apparatus comprising a supporting frame indicated generally at 70 which includes four rectangularly spaced support legs 72 supporting a lower rectangular frame structure comprising end rails 74 and 76 and side rails 78 and 80 all of which are rigidly interconnected. Two spaced end posts 82 and 84 extend substantially vertically upwardly from the corners of the aforementioned lower frame structure at one end thereof, and another pair of upwardly and outwardly extending end posts 86 and 88 are rigidly secured to and extend from the other end of said lower frame structure.

An intermediate frame structure comprises the end rail 90 extending between and connecting the end posts 86 and 88, and a pair of spaced side rails 92 and 94 secured to and extending from the end rail 90 toward the other end of the frame structure. The other ends of each of these side rails 92 and 94 are secured as by the brackets 96 to the vertically upstanding posts 82 and 84.

An upper rectangular frame structure comprises the spaced end rails 98 and 100 extending between and rigidly connected to the posts 86, 88 and 82, 84, respectively, and the side rails 102 and 104 rigidly secured to and extending between the posts 82, 86 and 84, 88, respectively. A cross rail 106 extends between and is rigidly secured to the side rails 102 and 104 between the ends of the latter and closer to the end posts 86 and 88 than the posts 82 and 84.

A fixed shaft 108 extends between the lower frame side rails 78 and 80. A bushing 110 is rotatably adjustably mounted on the shaft 108, and supports a hanger plate 112 to which the motor 114 is suitably secured, it being understood that a hanger rod or other suitable means well known in the art and not shown may be employed to adjust the position of the motor on the supporting frame 70. The output shaft of the motor drives a pulley 116 and, through a belt 118, a larger diameter pulley 120 secured to drive shaft 122 rotatably journaled in bearings 124 mounted on the side rails 92 and 94 of the intermediate frame structure. A small gear 126 at one end of the drive shaft 122 drives a larger gear 128 rigidly secured to cam shaft 130 extending between and having its opposite ends rotatably journaled in bearings 132 also on the side rails 92 and 94 of the intermediate frame structure alongside the drive shaft 122. A pair of identical drive cams 134 are respectively suitably secured to the opposite ends of the cam shaft 130 just outwardly of the side rails 92 and 94 of the intermediate frame structure.

It will be noted that drive from the drive shaft 122 to the gear 126 is through a conventional one-way clutch mechanism indicated generally at 136 in FIGURE 3 and of the type typically including two members rotatable relative to each other in one direction only, one of the members including a pin 138 adapted to be dogged with one end of a latch lever 140 rotatably supported on one end of a bracket 142 having its other end rigidly secured to the end rail 90 of the intermediate frame structure. The latch lever 140 normally needs no attention during operation of the apparatus herein disclosed, and normally dogs with the pin 138 to permit drive of the mechanism in only one direction; that is, the direction desired to operate the various set-up instrumentalities of the apparatus while, at the same time, permitting undogging of the pin for manual operation of the drive in a reverse fashion for maintenance or trouble shooting purposes, for example.

A drive sprocket 144 is suitably rigidly connected to the rotatable cam shaft 130 and is connected through a drive chain 146 to another drive sprocket 148 fixed to a bushing 150 rotatably supported on a fixed shaft 152 extending between and connected to the side rails 78 and 80 of the lower frame structure. Another drive sprocket 154 is also secured to the bushing 150 and mounts a conveyor drive chain 156 having clips 158 secured in spaced relation therealong for transporting cartons up a delivery chute 160. The conveyor chain 156 is entrained about another sprocket, not shown, at the other end of the delivery chute in a manner well known to those acquainted with this art, the upper run of the conveyor chain 156 riding in a central recessed opening 162 in the delivery chute.

The delivery chute 160 is rotatably adjustably supported on the fixed shaft 152 by means of a pair of brackets 164 journaled thereon and rigidly secured to the sides of the chute. An adjustable support rod 166 is suitably pivotally connected to the upper end of the delivery chute

in a manner well known in the art and, consequently, not shown, and has its lower end extending through a suitable aperture in a bracket 168 mounted between the ends of the end rail 76 of the lower frame structure. A pair of adjustable collars indicated at 170 are mounted on the rod 166 and embrace the bracket 168 to hold their delivery chute in any desired inclined position. A pair of upstanding retaining clips 172 are provided at the lower end of the delivery chute to prevent erected cartons from falling out of such end of the chute.

A substantially U-shaped guide chute including the upstanding side walls 174 and inclined end wall 176 is mounted on side rails 92 and 94 of the intermediate frame structure by means of the brackets 178. This inclined guide chute delivers directly into the lower end of the delivery chute 160 as indicated particularly in FIGURE 1, a pair of spaced spring clips 180 each having one end secured to an upper portion of the end wall 176 of the guide chute and projecting outwardly therefrom further facilitating delivery of erected cartons through the guide chute to the lower end of the delivery chute forward of the retaining clips 172. In view of the aforescribed construction, and as will appear more fully hereinafter, it will be readily apparent that fully erected or set-up cartons may be delivered through the guide chute to the lower end of the delivery chute, and picked up and moved therealong by the clips 158 carried by the conveyor chain 156 to the upper discharge end of the delivery chute.

A supply magazine for a stack of carton blanks in the collapsed condition of FIGURE 13 is indicated generally at 182 in FIGURE 1 and, referring additionally to FIGURES 2, 11 and 12, comprises a first pair of angle iron posts 184 and a second pair of angle iron posts 186 rigidly secured to the supporting frame of the apparatus in rectangularly spaced relationship as by means of the mounting brackets 188 connected between the respective angle iron posts and the side rails 102 and 104 of the upper frame structure of the apparatus as illustrated particularly in FIGURE 2. Thus, the respective pairs of angle iron posts 184 and 186 upstand vertically from the upper frame portion of the supporting frame 70 and constitute oppositely spaced and fixed wall means of the supply magazine to receive the collapsed carton blanks. A pair of laterally spaced elongate floor plates 190 each have one end rigidly secured to the end rail 100 of the upper frame structure of the supporting frame and project therefrom in parallel relationship beneath the magazine angle iron posts 186 toward the angle iron posts 184 so as to terminate generally midway therebetween and therebelow to form a floor means for the magazine.

A carton blank support bar 192 extends between and is suitably rigidly secured to the magazine angle iron posts 184, and is provided with a plurality of laterally spaced carton blank support fingers 194, herein shown to be seven in number, projecting inwardly of the magazine. The upper surfaces of a spaced pair of the support fingers are recessed as indicated at 196 in FIGURE 2 to receive a carton blank feeding finger to be hereinafter described. A pair of guide bars 198 are suitably adjustably mounted on an upper support bar 200 extending between the magazine angle iron posts 184 above the support bar 192, and depend therefrom in such a manner that their lower terminal ends are aligned with the support fingers having the recesses 196 to aid and facilitate guiding of the carton blank feeding fingers to be hereinafter described. As illustrated particularly in FIGURES 7 and 8, a mounting bracket 202 is also secured between the magazine angle iron posts 184 so as to support a pair of spaced depending spring clips 204 which cooperate to facilitate ejection of a fully set-up or erected carton into the guide chute in a manner to be described hereinafter.

With particular reference to FIGURES 2 and 11, the magazine construction also includes a pair of retaining arms 206 one end of each of which is pivotally con-

nected as indicated at 208 to a rearward portion of the respective magazine floor plates 190. The retaining arms cross each other in scissors fashion, and at their opposite ends mount retaining plates 210 including portions extending above and below the plane of the floor plates 190. A spring 212 interconnects the lower portions of each of the retaining plates 210, and acts to continuously urge the retaining arms into the position shown in FIGURE 11 in which the retaining plates extend inwardly of the magazine for engagement with the trailing edge of a lowermost carton blank in the magazine to be fed. Suitable stop means, herein shown to be in the form of adjustable stop bolts 214, are connected in the end rail 100 and include head members engageable with the respective retaining arms to limit movement thereof under the influence of the spring 212 into the magazine for the purpose aforementioned.

After loading the supply magazine 182 with a stack of collapsed paperboard carton blanks in the condition illustrated in FIGURE 13, the leading edge of the lowermost carton blank in the stack at the medial fold line 40 including the tongues 68 will rest upon the support fingers 194 while the trailing edge thereof formed by the locking panel or strip 22 will rest on the floor plates 190 adjacent the magazine angle iron posts 186. At this time, and prior to feeding such carton blank to the set-up instrumentalities to be described hereinafter, the pivotal retaining arms 206 are spread scissors fashion as illustrated in FIGURE 11 so that the upper portions of the retaining plates 210, which extend above the floor plates 190, engage the trailing edge of the carton blank to continuously urge such carton blank into supported engagement on the support fingers. However, means are provided, in conjunction with a carton feeding mechanism to be hereinafter described, for collapsing the retaining arms 206 outwardly of the magazine to the position illustrated in FIGURE 2 to free the trailing edge of the carton blank for movement to the right in FIGURE 2 to facilitate disengagement of the leading edge thereof from the support fingers 194, whereby the lowermost carton blank will drop entirely onto the floor plates 190 for subsequent feeding to the set-up instrumentalities.

Referring now particularly to FIGURES 1, 11 and 12, the magazine construction also includes means for adapting the magazine to hold and supply collapsed paperboard carton blanks having different dimensions or lengths between the leading and trailing edges thereof. More specifically, the lower end of each of the magazine angle iron posts 186 includes a recess 216 to receive an adapter member indicated generally at 218. Each of these adapter members includes a pair of substantially parallel oppositely disposed carton blank-engaging surfaces 220 and 222, there also being provided a guide surface 224 tapering from one end of the surface 220 and a guide surface 225 tapering from the other end of the other surface 222. A hinge pin 228 is adapted to be suitably secured to each of the magazine angle iron posts 186, and rotatably and slidably receives a respective one of the adapter members 218 on an axis closer to one of the carton blank-engaging surfaces than the other. A spring 230 acting between one side surface of each adapter member and the head of its associated hinge pin continuously biases the respective adapter members toward the respective magazine angle iron posts. A pair of stop pins 232 are mounted on the opposite side surface of each adapter member above and below and in the same common plane as the hinge pins 228 for abutment with a surface of the respective magazine angle iron posts 186. Thus, the stop pins 232 prevent rotation of the adapter members on the respective hinge pins while in the position of FIGURE 12, but the adapter members may be slid against the opposition of the spring 230 to free the stop pins from abutting engagement with the magazine angle iron posts thereby permitting the adapter members

5 to be rotated 180° and then replaced in the position illustrated in FIGURE 12 to select one or the other of the carton blank-engaging surfaces 220 and 222 for projection into the magazine. Since the carton blank-engaging surfaces are located at different distances from the axis of the hinge pins 228, it will be immediately apparent that any one given adapter member will permit adjustment of the effective carton blank-receiving length between the magazine angle iron posts 184 and 186 to receive carton blanks having two different dimensions between the leading and trailing edges thereof. Irrespective of which carton blank-engaging surface is selected in accordance with the particular carton blanks being fed, it will be readily apparent that each such surface is provided with the aforementioned guide surfaces to facilitate feeding carton blanks as they descend in the stack in the magazine into position on the floor plates 190 and support fingers 194. Needless, perhaps, to mention, it will also be apparent that more than two sizes of carton blanks can be handled by the magazine merely by providing more adapter members of corresponding configuration.

20 With particular reference to FIGURES 1, 2, 9 and 10, a folding head is indicated generally at 234 and a set-up and feeding head is indicated generally at 236. The folding head 234 comprises a laterally elongate carriage plate 238 extending between the side rails 102 and 104 of the upper frame structure of the supporting frame, and has suitably rigidly secured to the opposite ends thereof the 25 guide bushings 240 which are respectively slidably mounted on a pair of guide rods 242, each of which has one end rigidly secured to the end rail 100 of the upper frame structure and the other end thereof secured to a bracket 244 rigidly secured to and depending from the side rail members 102 and 104 of the upper frame structure between the ends of the latter. A generally rectangularly shaped open folding frame 246 has the upper portion thereof secured to the carriage plate 238 and depends therefrom. The upper and lower portions of the folding frame are provided with a suitable number of vertically aligned pairs of folding arms 248, herein shown to be eight pairs in accordance with the number of cross partition forming panel members to be folded on the carton blank in question, each arm having one end suitably rigidly secured to an upper or lower portion of the folding frame so as to project away therefrom. The other end of each of these folding arms is arcuately curved as illustrated particularly in FIGURE 9 to facilitate the folding operation on the cross partition forming panel members. Additionally, each of the folding arms is provided with a locking finger 250 suitably rigidly secured to one side surface thereof and projecting laterally therefrom so as to receive and hold one edge of a folded cross partition forming panel member to facilitate final erection of a 30 carton as will become more apparent hereinafter. In view of the foregoing description, it should be immediately apparent that the folding head 234 comprising carriage plate 238 and folding frame 246 is mounted for rectilinear reciprocation along supporting frame 70 by 35 means of guide bushings 240 and guide rods 242, power for such reciprocable movement being provided by a 40 drive means to be described hereinafter.

45 At this juncture, it should be noted that the carriage plate 238 is mounted immediately below the magazine floor plates 190 and, as aforementioned, the folding frame 246 depends from the carriage plate and hence below the floor plates 190 as clearly illustrated in the drawings. Furthermore, the central portion of the carriage plate, 50 and particularly the edge 252 thereof as illustrated particularly in FIGURE 9, is adapted to engage the lower portions of the retaining plates 210 on retaining arms 206 aforescribed to collapse them to the position of FIGURE 55 2 for feeding a carton blank from the support fingers 194 upon the carriage plate and entire folding head being 60

reciprocated to the position illustrated in FIGURES 1 and 2.

The set-up and feeding head 236 comprises a generally rectangular open set-up and feeding frame 254 including a plurality of oppositely projecting fingers 256 on the upper and lower portions thereof to provide support for the top wall forming panel members of a carton blank being erected as to be described hereinafter, these fingers being aligned and positioned relative to the folding arms of the folding frame to permit passage of the latter there-around as indicated particularly in FIGURE 10. Each end of the set-up and feeding frame 254 is suitably rigidly secured to a guide rod 258 which are respectively slidably mounted within guide bushings 260 rigidly secured to the carriage plate 238 and beneath the latter. The other ends of each of these guide rods are suitably rigidly secured to a generally U-shaped cross bar 262 having stop members 264 at opposite ends thereof adapted to abut the end posts 82 and 84 to limit travel of the set-up and feeding head in this direction under the influence of the drive means to be described. Thus, the set-up and feeding frame 254 is located in front of the folding frame 246, and the upper edge thereof is provided with a plurality of feeding blades or fingers 266, herein shown to be six in number, all of which project forwardly and upwardly from the upper edge of the set-up and feeding frame above the surface of the magazine floor plates 190, the narrower extreme outer feeding blades or fingers being inclined upwardly to a somewhat greater extent than the interior wider fingers or blades. Four rectangularly spaced stop members 268 are located in the respective four corners of the set-up and feeding frame 254 for abutment with the corresponding corners of the folding frame 246 as will appear hereinafter.

A pair of brackets 270 extend between the upper and lower portions of the set-up and feeding frame 254, and each pivotally mounts a latch lever 272 adapted to latching engage and disengage the lower portion of the folding frame 246. Each of the latch levers is continuously biased toward such latching engagement by the free ends of leaf springs 274 having their opposite ends secured to the cross bar 262 of the set-up and feeding head.

With the latch levers 272 engaged as illustrated particularly in FIGURES 1, 4 and 5, the folding head 234 and set-up and feeding head 236 are adapted to be reciprocated in unison along the supporting frame 70 from right to left in the aforementioned figures of the drawings by a drive means including the aforescribed drive cam 134. More specifically, and referring particularly to FIGURES 1 through 3, a pair of drive arms 276 each have one end suitably pivotally journaled for oscillation on the fixed shaft 108 and their other ends pivotally connected through a drive link 278 to a bracket depending from and suitably rigidly secured to the carriage plate 238 of the folding head 234. A cam follower roller 280 is rotatably mounted on each of the drive arms 276 for engagement with the respective drive cams 134. An arm extends from each of the drive arms 276 and pivotally mounts an idler plate 282 having springs 284 connected to the opposite ends thereof and similarly connected to the opposite ends of a similar idler plate 286 pivotally mounted on the respective drive cams at a suitable point spaced from the axis of rotation of the latter so as to continuously urge the drive arms and their cam follower rollers into engagement with the respective drive cams. Thus, as the respective drive cams rotate counterclockwise in FIGURE 1, the respective drive arms 276 will be oscillated counterclockwise to reciprocate the folding head 234 from right to left in the aforementioned figure of the drawings carrying the set-up and feeding head 236 in unison with it so long as the latch levers 272 are engaged between the respective heads aforementioned. Continued rotation of the drive cams will eventually result in clockwise movement of the drive arms to return the folding head and

set-up and feeding head to the position shown in FIGURE 1.

Referring particularly to FIGURES 1 and 2, a bottom tucking plate or blade 288 extends transversely between and below the side rails 102 and 104 of the upper frame structure of the supporting frame so as to be substantially aligned with the medial portion of the aforescribed folding head and set-up and feeding head. One end of the tucking plate or blade is suitably rigidly secured to a depending portion of the cross rail 106 and the other free end thereof extends toward the folding head and set-up and feeding head aforementioned. The free end of the tucking plate or blade is provided with a plurality of elongate openings 290 adapted to receive the cross partition forming panel members of a given carton blank after they have been folded into position for subsequent interlocking engagement with the bottom wall forming panel member of the carton blank. A pair of spaced receptacles 292 are also suitably secured to the cross rail 106 to receive therein cushioning springs 294 for a purpose to appear more fully hereinafter. Additionally, a suitable number of brackets 296 are spaced along the lower portion of the cross rail 106 to support spring fingers 298 mounting on the free ends thereof 25 ejecting fingers or cleats 300 to facilitate in ejecting a fully erected carton from the apparatus in a manner to be described.

Referring particularly to FIGURES 1 and 2, the apparatus also includes a second set-up head indicated generally at 302 and comprising a laterally elongate set-up frame indicated generally at 304 having its opposite ends suitably rigidly secured respectively to a pair of guide rods 306 which are respectively slidably mounted in guide bushings 308 suitably rigidly secured to the cross rail 106, the opposite ends of these guide rods being suitably rigidly secured to the opposite ends of a cross bar 310. The cross bar 310 is connected by a pair of return springs 312 to the cross rail 106 so as to continuously bias the set-up head 302 to the right and relative to the tucking plate or blade 288 to a position in a set-up zone on the apparatus as illustrated in FIGURES 1, 2 and 4 through 6. A latch lever 314 is pivotally connected to a bracket carried by the end rail 98 of the upper frame structure of the supporting frame, and includes a dogging notch 316 engageable with the cross bar 310 to lock the set-up head 302 in position in the set-up zone aforementioned. In particular, the latch lever prevents movement of set-up head 302 to the left in FIGURES 1 and 2 to an extreme retracted position until released by mechanism to be described hereinafter.

The set-up frame 304 of the set-up head 302 comprises a pair of laterally spaced end plates 318 interconnected by upper and lower frame bars 320 which rigidly mount in inclined relationship to each other the upper and lower laterally extending wall members 322 and 324, respectively, spaced slightly from each other to form a passage for receipt of the tucking plate or blade 288. A suitable number of plate members 326 are spaced along the upper wall member 322 and are suitably provided with a rough finish for initial engagement with the leading edge of a carton blank being fed thereto for a purpose and in a manner to be described hereinafter. Furthermore, a pair of feeding fingers 328 are suitably secured to the top portion of the upper wall member 322 of the set-up frame so as to be in vertical alignment with and pass beneath the guide bars 198, and enter the recesses 196 in the pair of support fingers 194 on the magazine for feeding the leading edge of a carton blank therefrom as will also appear more fully hereinafter. The lower wall member 324 of the set-up frame 304 is provided with a suitable number of slots to permit movement therethrough of the ejecting fingers or cleats 300. Also, a suitable number of spaced retaining fingers 330 are secured to and project outwardly from

the lower edge of the lower wall member of the set-up frame 304. A pair of stop or abutment rods 332 each have one end suitably rigidly secured to the respective end plates 318 of the set-up frame, and project therefrom for cooperation with the set-up and feeding head 236 in a manner to be described hereinafter. Also, a pair of unlatching fingers 334 each have one end fixedly secured to the end plates 318 of the set-up frame for cooperation with the latch levers 272 pivotally mounted on the set-up and feeding frame 254 to control unlatching thereof.

A pair of bell crank latch levers 336 are pivotally mounted on cross rail 106 adjacent the side rails 102 and 104 of the upper frame structure of the supporting frame and are adapted to selectively engage the end plates 318 of the set-up frame 304 to hold the latter in a retracted position away from the set-up zone of the apparatus as illustrated in FIGURE 7, and are selectively disengageable to permit the return springs 312 to return the set-up head 302 to the set-up zone or the position illustrated in FIGURES 1 and 4 through 6. To this end, one end of the respective latch levers 336 is pivotally connected through suitable joint connections in a link 338 to laterally projecting portions of a pair of latch control levers 340 pivotally connected to the side rail members 92 and 94 of the intermediate frame structure of the apparatus. The upper ends of these control levers are interconnected by a cross rod 342 carrying a central bracket 344 mounting an adjustable control member 346 which, as the control levers are oscillated as to be described hereinafter, will operate in timed relation with the rest of the set-up instrumentalities to control latching and unlatching engagement of the latch lever 314 with the cross bar 310 of the set-up head 302. Additionally, oscillation of these control levers operating through the links 338 similarly controls latching and unlatching engagement of the bell crank latch levers 336 with the end plates 318 of set-up frame 304. The control levers 340 are operated in accordance with the positions of the drive cams 134, drive arms 276 and the corresponding positions of the various set-up instrumentalities of the apparatus by means of an adjustable cam follower 348 located at the opposite end of each of the control levers from cross rod 342, and adapted to cooperate with the respective drive arms 276 whereby, upon oscillation of the drive arms counterclockwise in FIGURE 1, the control levers are rotated clockwise under the influence of springs 350 connecting the latter to the cross rail 106 to ultimately lift latch lever 314 and dispose latch levers 336 for latching engagement with set-up frame 304. Conversely, upon clockwise oscillation of the drive arms 276 in FIGURE 1, the control levers will pivot counterclockwise to ultimately dispose latch lever 314 in position to re-engage the cross bar 310, and operate the bell crank latch lever to the positions illustrated in FIGURE 2 to release the set-up head 302 from its retracted position for return to the set-up zone of the apparatus under the influence of return springs 312.

Referring now to the operation of the aforescribed apparatus, it will be understood that the motor 114 is energized to continuously rotatably drive the drive shaft 122 and cam shaft 130. As a result, the drive arms 276 are continuously oscillated about the axis of shaft 108 to reciprocate the folding head 234 in one direction and then the opposite direction on the supporting frame. Furthermore, drive is conducted through drive chain 146 to conveyor chain 156 to continuously operate the latter for conveying fully set-up or erected cartons.

FIGURE 1 illustrates the positions of the various set-up instrumentalities of the apparatus after a preceding carton blank has been erected and ejected from the apparatus, and the succeeding lowermost carton blank 20 in the stack in the magazine 182 has been ejected or fed from the support fingers 194 into position on the magazine floor plates 190 for subsequent feeding to the set-up

zone on the apparatus for erection of the same. At this time, the latch lever 314 is engaged with the cross bar 310 of the set-up head 302 to hold the set-up frame 304 at the forward or free end of the tucking plate or blade 288 in the set-up zone. Furthermore, the latch levers 272, under the influence of the leaf springs 274, latchingly engage the folding frame 246 so as to hold the folding head 234 and the set-up and feeding head 236 in predetermined spaced relation as the carriage plate 238 is reciprocated along the guide rods 242 from right to left in FIGURE 1 of the drawings under the influence of the aforescribed drive means.

The drive means then operates to move the various set-up instrumentalities to the FIGURE 4 position. In moving from the FIGURE 1 to the FIGURE 4 position, the feeding blades or fingers 266 on the set-up and feeding head 236 engage the medial fold line 50 between the top wall forming panel members 46 and 48 of the carton blank to feed the latter along the floor plates 190 toward the set-up head 302. The leading edge of the carton blank along the medial fold line 40 between the bottom wall forming panel members thereof will initially engage the upper wall member 322 of the set-up frame 304 and, due to the roughened or frictional surface of the plate members 326 carried thereby, will tend to be retarded in its feeding action toward the apex of the inclined wall members 322 and 324 of the set-up frame. During this feeding action, and prior to reaching the FIGURE 4 position, the rearward portion of the double ply portion of the carton blank is confined on the floor plates 190. As a result, due to the retarding action on the leading edge 40 of the carton blank, the bottom wall forming panel members 36 and 38 tend to and do expand somewhat, facilitating further expansion thereof as illustrated in FIGURE 4 after the double ply portion of the carton blank passes over the edges of the floor plates 190 and the leading edge 40 of the carton blank assumes the position shown.

In the FIGURE 4 position, the double ply portion of the carton blank has moved completely off of the floor plates 190 of the magazine as aforescribed, while the cover forming panel member 28 and locking panel or strip 22 thereof still extends to some extent onto the floor plates. At this time, the set-up and feeding head 236 is able, in response to continued reciprocation thereof with folding head 234, to begin further spreading the partially expanded carton blank. Thus, continued movement of the drive mechanism disposes the set-up instrumentalities in the FIGURE 5 position, at which time the carton blank is substantially fully expanded in the set-up zone of the apparatus. In this position, the bottom wall forming panel members 36 and 38 and top wall forming panel members 46 and 48 including cross partition forming panel members 52 and 54 are respectively engaged with and confined between the set-up frames 304 and 254 and interconnect the side wall forming panel members 32 and 44, the respective side wall forming panel members being guided and confined between the lower surfaces of the support bar 192 on the magazine and the retaining fingers 330 projecting from the lower wall member of the set-up frame 304. In particular, in the FIGURE 5 position, it will be noted that the top wall forming panel members including the cross partition forming panel members lie substantially flush with the set-up and feeding frame 254 for the subsequent folding operation on the cross partition forming panel members as will be described. Also, the ends of stop or abutment rods 332 engage the set-up and feeding frame 236, and unlatching fingers 334 are in position to unlatch the latch levers 272 to free the folding head 234 for reciprocable movement relative to the set-up and feeding head 236 and set-up head 302. Finally, and as shown more clearly in FIGURES 7 and 8, the lower ends of spring clips 204 are interposed between the carton blank and the set-up frame 304.

In the FIGURE 5 position or as close thereto as possible, the latch levers 272 are disengaged from the folding frame 246 due to abutment therewith of the unlatching fingers 334 carried by the set-up frame 304. Consequently, the folding head 234 and folding frame 246 thereof are free to move relative to the set-up and feeding head 236 along guide rods 258 from the FIGURE 5 position to the FIGURE 6 position, the set-up and feeding head being in abutment with the stop or abutment rods 332 carried by the set-up head 302 which is held stationary by the latch lever 314. Thus, as the drive means continues to operate, the folding frame 246 moves from the FIGURE 5 position to the FIGURE 6 position, and the fixed folding arms 248 pass through the set-up or feeding frame 254 and engage the cross partition forming panel members 52 and 54 to fold them inwardly of the partially erected carton between the side wall forming panel members and toward the bottom wall forming panel members thereof to the position shown in FIGURE 6. At this time, the edges of the cross partition forming panel members adjacent the top wall forming panel members of the carton blank are received between and locked by the respective folding arms and the locking fingers 259 carried thereby as indicated in FIGURE 6. Additionally, at this time, the folding frame 246 abuts the stop members 268 on the set-up and feeding frame 254 so that further reciprocation of the folding head 234 to the left in FIGURE 6 will of necessity carry with it the set-up and feeding head 236 and the set-up head 302 which is in direct engagement with the set-up and feeding head 236 through the stop or abutment rods 332.

As the drive means operates to reciprocate the afore-described mechanism from the position of FIGURE 4 through the position of FIGURE 5 to the position of FIGURE 6, the drive arms 276 will be oscillating counterclockwise in FIGURE 1 permitting the latch control levers 340 to rotate clockwise under the influence of the springs 350 as aforescribed. As the control levers so rotate, the adjustable control member 346 gradually rises until it is in a position to engage the free end of the latch lever 314 to undog the notch 316 thereof from the cross bar 310 of the set-up head 302. Additionally, as the control levers so rotate, the bell crank latch levers 336 are being returned from the unlatching position of FIGURE 2 to a position for engagement with the set-up frame 304 upon the latter reaching a full retracted position as will be described.

Thus, the latch lever 314 is undogged from the cross bar 310 after the folding operation aforescribed and with the various set-up instrumentalities in the positions illustrated in FIGURE 6. Consequently, further operation of the drive means now reciprocates the folding head 234, set-up and feeding head 236 and set-up head 302 in unison along the supporting frame due to the fact that each of these heads are in operative abutment with each other. Therefore, the various instrumentalities are reciprocated to the position of FIGURE 7 in which the set-up head 302 is illustrated in its retracted position rearwardly of the forward edge of the tucking plate or blade 288 which acts upon the medial fold line 40 between the bottom wall forming panel members 36 and 38 of the carton blank to tuck the latter inwardly of the expanded carton into interlocking engagement with the cross partition forming panel members as aforescribed. At this time, the bell crank latch levers 336 are in position to engage the end plates 318 of the set-up frame 304 to hold the entire set-up head 302 in its retracted position illustrated in FIGURE 7. Displacement of the carton blank from the FIGURE 6 to the FIGURE 7 position causes the ejecting fingers or cleats 300 to engage the edge of the carton side wall forming panel member 44, and also tension spring clips 204.

Thereafter, continued operation of the drive means operates to reciprocate the folding head 234 and set-up

and feeding head 236 on a return stroke toward the opposite end of the apparatus, the drive arms 276 oscillating clockwise in FIGURE 1 during this return movement. Due to such oscillation, the latch control levers 340 are rotated gradually counterclockwise in FIGURE 1 to ultimately operate the bell crank latch levers 336 to the disengaging position illustrated in FIGURE 2 to free the set-up head 302 for rapid return reciprocation to the set-up zone under the influence of return springs 312, while the latch lever 314 gradually lowers for re-engagement with the cross bar 310 of the set-up head 302 in its returned position.

More specifically, during return movement of the folding head 234 and set-up and feeding head 236 as described above, these instrumentalities will move from the FIGURE 7 position through the FIGURE 8 position to the position illustrated in FIGURE 1. The timing of the operation of the latch control levers 340 and the drive arms 276 is such that the folding head 234 and set-up and feeding head 236 will reach at least the position illustrated in FIGURE 8 before the bell crank latch members 336 are released for return movement of the set-up head 302. In this manner, the folding head and set-up and feeding head are permitted to return far enough to, first, clear the trailing edge of the cover forming panel member 28 of the fully erected carton for free delivery of the latter into the guide chute to the delivery chute and, secondly, to place the carriage plate 238 in position to depress the retaining arms 206 and retaining plates 210 out of engagement with the lowermost carton blank in the stack which is next to be fed to the set-up apparatus.

Thus, upon the folding head and set-up and feeding head reaching approximately the position illustrated in FIGURE 8, the bell crank latch levers have been disengaged, and the set-up head 302 is shown between its extreme latched retracted position of FIGURE 7 and its other extreme position at the forward edge of the tucking plate or blade 288 as illustrated in FIGURE 4. In so returning, the set-up head 302 abuts and provides the impetus for kicking the fully erected carton as illustrated in FIGURE 8 into the guide chute, the spring clips 204 and ejecting fingers or cleats 300 cooperating to provide a pivotal roll to the carton to facilitate this ejecting operation. When the set-up head 302 reaches its extreme position in the set-up zone at the forward edge of the tucking plate or blade as illustrated in FIGURE 4, movement thereof is arrested and cushioned by the cushioning springs 294 engaging cross bar 310, and the feeding fingers 328 project through and along the recesses 196 in the spaced pair of support fingers 194. Thus, the leading edge of the lowermost carton blank in the stack in the magazine is displaced from the support fingers so as to drop onto the floor plates 190 of the magazine as illustrated in FIGURE 1, it being understood that the carriage plate 238 has operated the retaining arms 206 sufficiently to free the trailing edge of the carton blank for this supply or feed operation.

In the FIGURE 8 position, the stop members 264 (FIGURES 9 and 10) carried by the cross bar 262 of the set-up and feeding head 236 are in abutment with the end posts 82 and 84 of the supporting frame to arrest further movement of the set-up and feeding head to the right in FIGURES 8 and 1. However, the drive means continues to reciprocate the folding head 234 to the right from the position of FIGURE 8 to the position of FIGURE 1 until such time as the guide bushings 260 abut the cross bar 262. During this relative reciprocation between folding head 234 and set-up and feeding head 236, the latch levers 272 ride up over the lower portion of the folding frame 246 to re-engage with the latter, thereby repositioning the parts as illustrated in FIGURE 1 to repeat the set-up cycle aforescribed.

While but one form of the invention has been shown and described, other forms will now be apparent to those skilled in the art. Therefore, it will be understood that

the embodiment shown in the drawings and described above is merely for illustrative purposes, and is not intended to limit the spirit and scope of the invention.

Other modes of applying the principle of my invention may be employed instead of the one explained, change being made as regards the means and the methods herein disclosed provided those stated by any of the following claims or their equivalent be employed.

I therefore particularly point out and distinctly claim as my invention:

1. A method for setting-up a collapsed paperboard carton blank into an erected cellular carton, said blank being of the type characterized by a connected series of panel members adapted to be erected into side wall forming members and a bottom wall forming member of an erected carton and including cross partition forming members foldable out of the plane of a top wall forming member into interlocking engagement with said bottom wall forming member; said method comprising the steps of expanding said carton blank with said top and bottom wall forming members opposite each other and connected between said side wall forming members, folding said cross partition forming members toward said bottom wall forming member, and moving said expanded carton blank to engage the bottom wall forming member thereof with tucking means to move said bottom wall forming member toward said top wall forming member and into interlocking engagement with said cross partition forming members.

2. A method for setting-up a collapsed paperboard carton blank into an erected cellular carton, said blank being of the type characterized by a connected series of panel members adapted to be erected into side wall forming members and a bottom wall forming member of an erected carton and including cross partition forming members foldable out of the plane of a top wall forming member into interlocking engagement with said bottom wall forming member; said method comprising the steps of expanding said carton blank with said top and bottom wall forming members opposite each other and connected between said side wall forming members, folding said cross partition forming members toward said bottom wall forming member, and bodily moving said top and bottom wall forming members in unison to engage said bottom wall forming member with tucking means to move said bottom wall forming member toward said top wall forming member and into interlocking engagement with said cross partition forming members.

3. A method for setting-up a collapsed paperboard carton blank into an erected cellular carton, said blank being of the type characterized by a connected series of panel members adapted to be erected into side wall forming members and a bottom wall forming member of an erected carton and including cross partition forming members foldable out of the plane of a top wall forming member into interlocking engagement with said bottom wall forming member; said method comprising the steps of expanding said carton blank with said top and bottom wall forming members opposite each other and connected between said side wall forming members, holding said top and bottom wall forming members substantially stationary while folding said cross partition forming members toward said bottom wall forming member, and bodily moving said top and bottom wall forming members in unison to engage said bottom wall forming member with tucking means to move said bottom wall forming member toward said top wall forming member and into interlocking engagement with said cross partition forming members.

4. A method for setting-up a collapsed paperboard carton blank into an erected cellular carton, said blank being of the type characterized by a connected series of panel members adapted to be erected into side wall forming members and a bottom wall forming member of an erected carton and including cross partition forming

members foldable out of the plane of a top wall forming member into interlocking engagement with said bottom wall forming member; said method comprising the steps of moving said side wall forming members away from each other to expand said carton blank with said top and bottom wall forming members opposite each other and connected between said side wall forming members, holding said top and bottom wall forming members substantially stationary while folding said cross partition forming members toward said bottom wall forming member, and bodily moving said top and bottom wall forming members in unison to engage said bottom wall forming member with fixed tucking means to move said bottom wall forming member toward said top wall forming member and into interlocking engagement with said cross partition forming members.

5. A method for setting-up a collapsed paperboard carton blank into an erected cellular carton, said blank being of the type characterized by a connected series of panel members adapted to be erected into side wall forming members and a bottom wall forming member of an erected carton and including cross partition forming members foldable out of the plane of a top wall forming member into interlocking engagement with said bottom wall forming member; said method comprising the steps of confining an expanded carton blank between a pair of set-up heads with said top and bottom wall forming members connected between said side wall forming members opposite to each other and respectively in engagement with said set-up heads, folding said cross partition forming members between said side wall forming members and toward said bottom wall forming member, and moving said set-up heads in unison to engage said bottom wall forming member with tucking means to move said bottom wall forming member toward said top wall forming member and into interlocking engagement with said cross partition forming members.

6. A method for setting-up a collapsed paperboard carton blank into an erected cellular carton, said blank being of the type characterized by a connected series of panel members adapted to be erected into side wall forming members and a bottom wall forming member of an erected carton and including cross partition forming members foldable out of the plane of a top wall forming member into interlocking engagement with said bottom wall forming member; said method comprising the steps of confining said carton blank between a pair of set-up heads to move said side wall forming members away from each other to expand said carton blank with said top and bottom wall forming members connected between said side wall forming members opposite to each other and respectively in engagement with said set-up heads, folding said cross partition forming members between said side wall forming members and toward said bottom wall forming member, and moving said set-up heads in unison to engage said bottom wall forming member with tucking means to move said bottom wall forming member toward said top wall forming member and into interlocking engagement with said cross partition forming members.

7. A method for setting-up a collapsed paperboard carton blank into an erected cellular carton, said blank being of the type characterized by a connected series of panel members adapted to be erected into side wall forming members and a bottom wall forming member of an erected carton and including cross partition forming members foldable out of the plane of a top wall forming member into interlocking engagement with said bottom wall forming member; said method comprising the steps of confining said carton blank between a pair of set-up heads to move said side wall forming members away from each other to expand said carton blank with said top and bottom wall forming members connected between said side wall forming members opposite to each other and respectively in engagement with said set-up heads,

holding said set-up heads substantially stationary while folding said cross partition forming members between said side wall forming members and toward said bottom wall forming member, and moving said set-up heads in unison to engage said bottom wall forming member with tucking means to move said bottom wall forming member toward said top wall forming member and into interlocking engagement with said cross partition forming members.

8. A method for setting-up a collapsed paperboard carton blank into an erected cellular carton, said blank being of the type characterized by a connected series of panel members adapted to be erected into side wall forming members and a bottom wall forming member of an erected carton and including cross partition forming members foldable out of the plane of a top wall forming member into interlocking engagement with said bottom wall forming member; said method comprising the steps of feeding a single carton blank from a stack thereof into a set-up zone, confining said carton blank between a pair of set-up heads in said set-up zone to move said side wall forming members away from each other to expand said carton blank with said top and bottom wall forming members connected between said side wall forming members opposite to each other and respectively in engagement with said set-up heads, holding said set-up heads substantially stationary while folding said cross partition forming members between said side wall forming members and toward said bottom wall forming member, and moving said set-up heads in unison to engage said bottom wall forming member with fixed tucking means to move said bottom wall forming member toward said top wall forming member and into interlocking engagement with said cross partition forming members.

9. An apparatus for setting-up a collapsed paperboard carton blank into an erected cellular carton, said blank being of the type characterized by a connected series of panel members adapted to be erected into side wall forming members and a bottom wall forming member of an erected carton and including cross partition forming members foldable out of the plane of a top wall forming member into interlocking engagement with said bottom wall forming member; said apparatus comprising a supporting frame including a set-up zone, a first set-up head, means mounting said first set-up head for movement on said supporting frame between a retracted position and said set-up zone, a tucking blade fixedly mounted on said supporting frame, a second set-up head, means mounting said second set-up head for movement on said supporting frame relative to said tucking blade between said set-up zone and a position retracted therefrom, drive means operatively connected to said first set-up head to move the latter along said supporting frame, means for feeding a carton blank into said set-up zone whereby said carton blank is confined between said first and second set-up heads in said set-up zone to move said side wall forming members away from each other to expand said carton blank with said top and bottom wall forming members connected between said side wall forming members opposite to each other and in respective engagement with said first and second set-up heads, means for folding said cross partition forming member inwardly of said expanded carton blank in said set-up zone, and abutment means interconnecting said set-up heads for movement of said second set-up head toward its retracted position upon further movement of said first set-up head whereby said tucking blade engages said bottom wall forming member and moves the latter toward and into a final set-up position interlocking with said cross partition forming members.

10. The apparatus defined in claim 9 in which said means for feeding a carton blank into said set-up zone comprises a supply magazine including floor means secured to one end of said supporting frame above said first set-up head to receive a stack of carton blanks, and a plurality

of spaced feeding fingers mounted on said first set-up head and projecting above said floor means of said magazine for engagement with a carton blank thereon for feeding the latter to said set-up zone upon movement of said first set-up head from its retracted position to said set-up zone.

11. An apparatus for setting-up a collapsed paperboard carton blank into an erected cellular carton, said blank being of the type characterized by a connected series of panel members adapted to be erected into side wall forming members and a bottom wall forming member of an erected carton and including cross partition forming members foldable out of the plane of a top wall forming member into interlocking engagement with said bottom wall forming member; said apparatus comprising a supporting frame including a set-up zone, a folding head including means engageable with said cross partition forming members to fold the latter in said set-up zone, means mounting said folding head for movement on said supporting frame between a retracted position and said set-up zone, a first set-up head, means mounting said first set-up head on said folding head for relative movement therebetween, latch means selectively operable to lock said heads in predetermined spaced relationship for movement in unison on said supporting frame and to unlock said heads for movement of said folding head relative to said first set-up head, a tucking blade fixedly mounted on said supporting frame, a second set-up head, means mounting said second set-up head for movement on said supporting frame relative to said tucking blade between said set-up zone and a position retracted therefrom, drive means connected to said folding head to move the latter along said supporting frame, means for feeding a carton blank into said set-up zone whereby said carton blank is confined between said first and second set-up heads in said set-up zone to move said side wall forming members away from each other to expand said carton blank with said top and bottom wall forming members connected between said side wall forming members opposite to each other and in respective engagement with said first and second set-up heads, abutment means interconnecting said set-up heads for movement of said second set-up head toward its retracted position upon further movement of said first set-up head, and means for unlocking said latch means upon expanding said carton blank in said set-up zone, said drive means being operable upon unlocking of said latch means to further move said folding head relative to said first set-up head whereby said folding means fold said cross partition forming members inwardly of said expanded carton blank and said folding head abuts said first set-up head, said drive means being operable to further move said folding head and set-up heads in unison and relative to said tucking blade whereby the latter engages said bottom wall forming member and moves the latter toward and into a final set-up position interlocking with said cross partition forming members.

12. The apparatus as defined in claim 11 in which said means for unlocking said latch means comprises an unlatching finger fixed to and projecting from said second set-up head for unlatching engagement with said latch means upon expanding said carton blank in said set-up zone.

13. An apparatus for setting-up a collapsed paperboard carton blank into an erected cellular carton, said blank being of the type characterized by a connected series of panel members adapted to be erected into side wall forming members and a bottom wall forming member of an erected carton and including cross partition forming members foldable out of the plane of a top wall forming member into interlocking engagement with said bottom wall forming member; said apparatus comprising a supporting frame including a set-up zone a folding head, means mounting said folding head for movement on said supporting frame between a retracted position and said set-up zone, a plurality of spaced folding arms mounted

on said folding head and projecting therefrom for engagement with and folding said cross partition forming members in said set-up zone, a first set-up head, means mounting said first set-up head on said folding head in front of the latter for relative movement therebetween, first latch means selectively operable to lock said heads in predetermined spaced relationship for movement in unison on said supporting frame and to unlock said heads for movement of said folding head relative to said first set-up head, a tucking blade fixedly mounted on said supporting frame, a second set-up head, means mounting said second set-up head for movement on said supporting frame relative to said tucking blade between said set-up zone and a position retracted therefrom, second latch means selectively operable to lock said second set-up head in said set-up zone and to unlock said second set-up head for movement toward its retracted position, third latch means selectively operable to lock said second set-up head in its retracted position and to unlock said second set-up head for movement toward said set-up zone, spring return means acting between said supporting frame and said second set-up head to return the latter to said set-up zone upon unlocking of said third latch means, drive means connected to said folding head to move the latter along said supporting frame, means for feeding a carton blank into said set-up zone and confining said carton blank between said first and second set-up heads in said set-up zone to move said side wall forming members away from each other to expand said carton blank with said top and bottom wall forming members connected between said side wall forming members opposite to each other and in respective engagement with said first and second set-up heads, abutment means interconnecting said set-up heads for movement of said second set-up head toward its retracted position upon further movement of said first set-up head, means for unlocking said first latch means upon expanding said carton blank in said set-up zone, said drive means being operable upon unlocking of said first latch means to further move said folding head relative to and toward said first set-up head whereby said folding arms engage and fold said cross partition forming members inwardly of said expanded carton blank and said folding head abuts said first set-up head, means for unlocking said second latch means upon folding said cross partition forming members, said drive means being operable to further move said folding head and said set-up heads in unison and relative to said tucking blade whereby the latter engages said bottom wall forming member and moves the latter toward and into a final set-up position interlocking with said cross partition forming members, said third latch means being operable to lock said second set-up head in its retracted position, said drive means being operable to return said first set-up head and said folding head toward its retracted position, and means for unlocking said third latch means for return of said second set-up head to said set-up zone under the influence of said spring return means after said first set-up head and folding head have been returned to a predetermined position on said supporting frame, whereby the thrust of said second set-up head in returning to said set-up zone provides the impetus for ejecting the fully erected carton from said set-up zone.

14. An apparatus for setting-up a collapsed paperboard carton blank into an erected cellular carton, said blank being of the type characterized by a connected series of panel members adapted to be erected into side wall forming members and a bottom wall forming member of an erected carton and including cross partition forming members foldable out of the plane of a top wall forming member into interlocking engagement with said bottom wall forming member; said apparatus comprising a supporting frame including a set-up zone, a folding head, means mounting said folding head for reciprocation on said supporting frame between a retracted position and said set-up zone, a plurality of spaced folding arms fixedly mounted on said folding head and projecting there-

from for engagement with and folding said cross partition forming members in said set-up zone, a first set-up head, means mounting said first set-up head on said folding head in front of the latter for relative reciprocation therebetween, first latch means selectively operable to lock said heads in predetermined spaced relationship for reciprocation in unison along said supporting frame and to unlock said heads for reciprocation of said folding head relative to said first set-up head, a tucking blade fixedly mounted on said supporting frame, a second set-up head, means mounting said second set-up head for reciprocation on said supporting frame relative to said tucking blade between said set-up zone and a position retracted therefrom, second latch means selectively operable to lock said second set-up head in its retracted position and to unlock said second set-up head for reciprocation toward said set-up zone, spring return means acting between said supporting frame and said second set-up head to return the latter to said set-up zone upon unlocking of said second latch means, drive means connected to said folding head to reciprocate the latter along said supporting frame, means for feeding a carton blank into said set-up zone whereby said carton blank is confined between said first and second set-up heads in said set-up zone to move said side wall forming members away from each other to expand said carton blank with said top and bottom wall forming members connected between said side wall forming members opposite to each other and in respective engagement with said first and second set-up heads, abutment means interconnecting said set-up heads for reciprocation of said second set-up head toward its retracted position upon further reciprocation of said first set-up head, means for unlocking said first latch means upon expansion of said carton blank in said set-up zone, said drive means being operable upon unlocking of said first latch means to further reciprocate said folding head relative to and toward said first set-up head whereby said folding arms pass through said folding head and fold said cross partition forming members inwardly of said expanded carton blank and said folding head abuts said first set-up head, said drive means being operable to further reciprocate said folding head and set-up heads in unison and relative to said tucking blade whereby the latter engages said bottom wall forming member and moves the latter toward and into a final set-up position interlocking with said cross partition forming members, said second latch means being operable to lock said second set-up head in its retracted position, said drive means being operable to return said first set-up head and said folding head toward its retracted position, and means for unlocking said second latch means for return of said second set-up head to said set-up zone under the influence of said spring return means after said first set-up head and folding head have been returned to a predetermined position on said supporting frame, whereby the thrust of said second set-up head in returning to said set-up zone provides the impetus for ejecting the fully erected carton from said set-up zone.

15. The apparatus as defined in claim 14 further comprising a locking finger secured to each of said folding arms between the ends of the latter and projecting laterally therefrom to receive and hold an edge of a cross partition forming member after folding the latter.

16. The apparatus as defined by claim 14 in which said drive means comprises a power driven drive cam rotatably supported on said supporting frame, a drive arm pivotally mounted on said supporting frame and including a cam follower roller engageable with said drive cam, spring means continuously urging said cam follower roller into engagement with said drive cam, link means connecting said drive arm to said folding head; and in which said means for unlocking said second latch means comprises a latch control lever pivotally mounted on said supporting frame and including means engageable with said second latch means to control the latter, and follower means on said latch control lever engageable with said drive arm to

pivot said latch control lever in timed relationship to operation of said drive means.

17. The apparatus as defined in claim 14 in which said means for feeding a carton blank into said set-up zone comprises a supply magazine secured to one end of said supporting frame and including oppositely spaced wall means and floor means above said first set-up head for receiving a stack of carton blanks, a plurality of spaced support fingers secured along a lower portion of one of said wall means and projecting inwardly of said magazine above said floor means for supporting the leading edge of the lowermost carton blank in said stack above said floor means, a plurality of spaced feeding fingers mounted on said first set-up head and projecting above said floor means of said magazine for engagement with the lowermost carton blank in said stack for feeding the latter from said magazine, and a plurality of spaced ejecting fingers mounted on said second set-up head and projectable through said one wall means of said magazine upon return of said second set-up head to said set-up zone to eject the leading edge of the lowermost carton blank in said stack onto said floor means of said magazine.

18. The apparatus as defined in claim 17 in which said supply magazine further includes a pair of crossed retaining arms each having one end pivotally connected to said floor means at spaced points thereon adjacent the other of said wall means exteriorly of said magazine, a retaining plate respectively secured to the other ends of said retaining arms and including portions extending above and below said floor means, spring means interconnecting the portions of said retaining plates below said floor means and continuously urging pivotal movement of said retaining arms to dispose said retaining plates within said magazine with the upper portions thereof engaging the trailing edge of the lowermost carton blank in said stack to urge the leading edge thereof onto said support fingers, and adjustable stop means engageable with said retaining arms to limit pivotal movement thereof and to position said retaining plates within said magazine in accordance with the distance between the leading and trailing edges of the carton blanks in said stack, said folding head in its retracted position being engageable with the lower portions of said retaining plates to pivot the latter out of engagement with the trailing edge of the lowermost carton blank in said stack to permit ejection of the leading edge thereof from said support fingers by said ejecting fingers.

19. Apparatus for supplying a collapsed paperboard carton blank to mechanism for erecting said blank into a cellular carton, said apparatus comprising a supporting frame, a supply magazine secured to said supporting frame and including oppositely spaced wall means and floor means for receiving a stack of said carton blanks, a plurality of spaced support fingers secured along a lower portion of one of said wall means and projecting inwardly of said magazine above said floor means for retaining the leading edge of the lowermost carton blank in said stack above said floor means, a feed mechanism mounted for reciprocation on said supporting frame beneath said floor means of said magazine between a retracted pick-up position and a forward feeding position, a plurality of spaced feeding fingers mounted on said feed mechanism and projecting above said floor means of said magazine for engagement with the lowermost carton blank in said stack for feeding the latter from said magazine, and an ejecting mechanism mounted for reciprocation on said supporting frame between a retracted position and an ejecting position adjacent said one wall means of said magazine, said ejecting mechanism including a plurality of spaced ejecting fingers projectable through said one wall means of said magazine with said ejecting mechanism in said ejecting position to eject the leading edge of the lowermost carton blank in said stack onto said floor means of said magazine.

20. The apparatus as defined in claim 19 further com-

prising a pair of crossed retaining arms each having one end pivotally connected to said floor means at spaced points thereon adjacent the other of said wall means exteriorly of said magazine, a retaining plate respectively secured to the other ends of said retaining arms and including portions extending above and below said floor means, spring means interconnecting the portions of said retaining plates below said floor means and continuously urging pivotal movement of said retaining arms to dispose said retaining plates within said magazine with the upper portions thereof engaging the trailing edge of the lowermost carton blank in said stack to urge the leading edge thereof onto said support fingers, adjustable stop means engageable with said retaining arms to limit pivotal movement thereof and to position said retaining plates within said magazine in accordance with the distance between the leading and trailing edges of the carton blanks in said stack, and means for operating said feed mechanism and said ejecting mechanism in timed relationship whereby said feed mechanism engages the lower portions of said retaining plates to pivot the latter out of engagement with the trailing edge of the lowermost carton blank in said stack to permit ejection of the leading edge thereof from said support fingers by said ejecting fingers.

21. The apparatus as defined in claim 19 further comprising an adapter member, a hinge pin including a head pivotally mounting said adapter member on said other wall means of said magazine above said floor means thereof, said adapter member including a pair of substantially parallel carton blank-engaging surfaces spaced different distances from said hinge pin, a guide surface tapering away from one end of each of said carton blank-engaging surfaces at opposite ends of said adapter member, stop means on said adapter member engageable with said other wall means to prevent pivotal movement of said adapter member on said hinge pin, and spring biasing means acting between said head of said hinge pin and said adapter member to urge said stop means into position to engage said other wall means, said adapter member being slidable on said hinge pin to move said stop means out of engagement with said other wall means against the influence of said spring biasing means, whereby said adapter member may be pivoted to select one of said carton blank-engaging surfaces thereon for projection beyond said other wall means into said magazine in accordance with the distance between the leading and trailing edges of the carton blanks in said stack.

22. Adapter means for a supply magazine of the type comprising oppositely fixedly spaced wall means for receiving stacks of collapsed carton blanks of varying dimensions between said wall means, said adapter means comprising an adapter member including a pair of substantially parallel carton blank-engaging surfaces, a hinge pin including a head at one end thereof slidably and rotatably supporting said adapter member on an axis closer to one of said carton blank-engaging surfaces than the other, the other end of said hinge pin being adapted to be secured to one of said wall means, spring means acting between the head of said hinge pin and said adapter member to continuously urge the latter to slide along said hinge pin toward said one wall means, and stop means projecting from said adapter member for engagement with said one wall means to prevent rotation of said adapter member on said hinge pin, said adapter member being slidable on said hinge pin against said spring means to release said stop means from said one wall means and thereafter being rotatable on said hinge pin to select one of said carton blank-engaging surfaces for projection beyond said one wall means into said magazine.

23. The adapter means as defined in claim 22 further comprising a guide surface tapering away from one end of each of said carton blank-engaging surfaces at opposite ends of said adapter member.

24. The adapter means as defined in claim 22 in

which said stop means comprise a pair of stop pins projecting from said adapter member parallel to and in a common plane with the axis of said hinge pin.

25. The adapter means as defined in claim 22 further comprising a guide surface tapering away from one end of each of said carton blank-engaging surfaces at opposite ends of said adapter member, and in which said stop means comprise a pair of stop pins projecting from said adapter member parallel to and in a common plane with the axis of said hinge pin.
